UNITED STATES PATENT OFFICE.

EDWIN A. GROZIER, OF NEW YORK, AND FRANK P. ANDERSON, OF BROOKLYN; SAID ANDERSON ASSIGNOR TO FREDERIC A. DUNEKA, OF NEW YORK, N. Y.

BASE-BALL BULLETIN-BOARD.

SPECIFICATION forming part of Letters Patent No. 427,508, dated May 6, 1890.

Application filed December 17, 1889. Serial No. 334,144. (No model.)

To all whom it may concern:

Be it known that we, EDWIN A. GROZIER, of New York, in the county and State of New York, and FRANK P. ANDERSON, residing at 5 Brooklyn, in the county of Kings and State of New York, have invented certain new and useful Improvements in Base-Ball Bulletin-Boards, of which the following is a specification, reference being had therein to the accompanying drawings.

This invention relates to bulletin or display boards specially intended to show the progress of a game of base-ball.

The object of the invention is to produce 15 a bulletin-board which may be posted in a conspicuous place, as the front of a newspaper-office or in a public hall or gathering-place, on which the proceedings of a base-ball game which is under way at some distant 20 point may be graphically illustrated.

The operator at the bulletin-board has communication by telegraph or telephone with the base-ball ground. The names of the clubs and players and their batting position 25 are displayed on the face of the board. The movement of the players at bat is delineated mechanically by the operator as soon as a dispatch is received from the grounds. The number of runs is denoted by a large figure and 30 the number of outs by a visible signal, which may be changed by the operator to show the exact progress of the game.

Figure 1 is a face view of the improved bulletin-board, some of the lettering omitted. 35 Fig. 2 is a broken section on the line $x-x$, Fig. 1. Fig. 3 is a broken section on the line $y-y$, Fig. 1. Fig. 4 is a broken cross-section on line $z-z$, Fig. 2. Fig. 5 is a section on the plane of line $s-s$ parallel with the face of the board. 40 Fig. 6 is a broken rear elevation on part of the board, as hereinafter explained.

A indicates a bulletin-board constructed of any well-known material. In a conspicuous place on the face of the board a diamond field 45 b is marked. Along the line of this diamond there is a groove or way c , preferably undercut. In this groove a number of cords or endless belts d are arranged to run over suitable pulleys e , (or rounded surfaces will answer in

lieu of pulleys.) Two cords d are shown in 50 the groove, but any number may be used. Three will generally be enough for any purpose. These cords and their supports constitute a mechanical conveyer. The cords may pass through the board near one corner of the 55 diamond, or may extend into other convenient position for operation from the rear or side of the board. The illustration shows the cords passing through aperture e near the third base and thence extending around pulleys f at the 60 back of the board. In practice the cords can generally be best manipulated from behind the home-base.

The cords may be worked by handles g on the pulleys or in other convenient manner. 65 Each cord carries one or more clips d , of wire or light metal, extending out through the slot in the face of the board in position to carry a tag or marker i in front of the face of the board.

The markers i indicate the players at bat, and by means of the cords can be moved along from base to base. The markers may bear the numbers, names, or portraits of the players, so that the observer of the board may 75 know each one. The operator by means of the cords can move the markers (designating players) from base to base, and, in fact, indicate their actual movements with great accuracy.

It has been found in using a bulletin-board to indicate the progress of a ball-game that it was difficult to see the figures denoting outs from any position a little to one side of the front. To avoid this objection the present device has been made with three openings 1 2 3 to denote the outs. The surface behind the openings is painted the same color as their margin, so that the holes are hardly visible from the front of the board. In a recess m in rear of these openings we place a slide o , having its front painted in strong contrast with the color of the board. The slide will preferably be of the color of the club it is intended to denote, and the slide may have 85 a handle p , which will swing into notches q at the side of the groove r and hold the slide 90 at any desired elevation. Thus when there

- is one player out the red slide *o* may be moved up in front of hole 1 and a red disk will be shown through hole 1 and be visible at quite an angle from the front of the board.
- 5 5 So when two players are out the slide can be moved another notch, to show at hole 2, and so on. It is obvious that the "outs" may all be shown at one set of holes, and the colors of the outs may be shown by simply changing the slides; also, that the piece may be moved up, down, or sidewise, or may be made in sections, with the same result, to denote through an opening the outs made by a club of players.
- 10 15 To denote the runs made it is desirable to have larger figures than can be conveniently marked on the board. For this purpose a rolling curtain or belt with the numbers painted thereon may be used. The letter *t* indicates such a belt, and *w w* the rollers on which it is wound back and forth. These may be turned by cranks *w'*. There should be one of these belts at each side of the board, and the figure on the face of the belt will show 20 25 through the hole A' A'.
- By the device above described the progress of a base-ball game can be illustrated with a graphic accuracy which is comparable to an actual view of the game.
- 30 35 To secure the greatest realistic effects, the players may be actually delineated on the board, and the club colors of contesting clubs should be used in the marking devices as far as possible.
- 35 What we claim is—
1. A base-ball bulletin-board showing a diamond or representation of a base-ball field, a mechanical conveyer constructed to have movement along such diamond, and a marker 40 representing a player attached to said con-

veyer, in combination, substantially as described.

2. A base-ball bulletin-board having a groove along the line of the diamond field, a cord or belt running in said groove, and a projecting clip attached to the cord in position to support a marker, in combination, substantially as described. 45

3. A base-ball bulletin-board having a diamond-shaped groove in its face, endless belts 50 supported in said groove and extending outside at some portion of their length, markers on said belts, and supporting-pulleys for said extended cords outside the groove, in combination, substantially as described. 55

4. A base-ball bulletin-board having a series of openings in its face with a background behind the openings generally resembling the face, a slide of contrasting color between the openings and the background, and a retaining-catch by which the slide can be secured in several positions, so as to be visible through one or a number of the openings, as desired, all combined substantially as set forth. 60

5. The combination, with a base-ball bulletin-board having the representation of a ball-field thereon, of a mechanical carrier along the line of the diamond and markers carried thereby, a series of openings to denote the outs, and a piece of contrasting color moving 65 behind said openings, and a movable apron carrying figures to denote the number of runs, all substantially as described. 70

In testimony whereof we affix our signatures in presence of two witnesses.

EDWIN A. GROZIER.
FRANK P. ANDERSON.
